OF WASHINGTON.

AUTOMATIC HAMMER.

1,310,574.

Specification of Letters Patent. Patented July 22, 1919.

Application filed October 5, 1917. Serial No. 194,849.

To all whom it may concern:

Be it known that we, GEORGE L. KOLLOCK, a citizen of the United States, residing at Seattle, in the county of King and State of Washington, and ROBERT P. MARTIN, a citizen of the United States, residing at Seattle, in the county of King and State of Washington, have invented certain new and useful Improvements in Automatic Hammers, the following being a full, clear, and exact disclosure of the one form of our invention which we at present deem preferable.

For a detailed description of the present form of our invention, reference may be had to the following specification and to the accompanying drawing forming a part thereof, wherein

Figure 1 is a longitudinal section of our device;

Fig. 2 is a similar section of the hammer part with the cam in elevation;

Fig. 3 is a transverse section on the line 3—3 of Fig. 1;

Fig. 4 is a similar section on the line 4—4 of Fig. 1;

Figs. 5 and 6 show details.

Our invention relates to a spring-actuated hammer, wherein the spring is periodically put under tension by means of an electric motor and periodically released in order to give the hammer an impact pressure corresponding to the force stored up in the spring by its previous tensioning. The electric motor has a continuous rotary motion which is converted into the periodic movement involved in the aforesaid tensioning of the spring, by the agency of a cam which is rotated by the motor and acts upon the spring through one or more inclined surfaces of a saw tooth form, which are engaged by the device which act upon the spring. The said engaging devices are rollers which ride upon the inclined surfaces of the cam, putting the spring under tension as they travel up the said surfaces, and releasing the spring when they drop off the saw tooth points. One purpose of our invention is to produce a practicable form of portable tool with the armature shaft of the motor substantially in line with the reciprocating hammer element or striker. This not only gives a compact construction but also utilizes the weight of the motor as an abutment to absorb the reaction of the blow or impact. We also

provide against side strains and against unbalanced strains on opposite sides of the axis of the tool.

Referring to the drawing, A represents one section of a cylindrical longitudinal casing, which serves at the same time as the yoke of the motor field-magnet B, and C is the motor-armature journaled to rotate between the field-magnet poles. The motor is preferably of the bipolar type. The upper end of the casing A is closed by a cap D which affords a bearing for the armature shaft and also contains the commutator brushes or contacts E of the motor as appears in Fig. 6. The opposite end of the casing A is closed by a disk F in which the other end of the armature shaft is journaled. A' represents a second section of casing having a screw-joint connection with the section A and containing the hammer portion of the apparatus. A fan G is provided at the left-hand end of the motor and ventilating openings a a are formed in the shell A through which air may be drawn by the fan for cooling the apparatus.

The reduced portion of the shell A' carries the actuating spring K which is coiled around the shaft of the hammer H concentrically therewith. A nut h is screwed on the lower end of the hammer serving as an abutment for one end of the spring K and also as a means for adjusting the spring tension. Openings H' in the nut h provide for the flow of air within the casing section and for the admission of air which will be drawn up through the tool through suitable ducts by means of the fan G. The upper end of the hammer-element, or striker, H is provided with a squared portion H' which passes through a square hole in the disk L to prevent its rotation and also with a cylindrical head H² that carries the rollers J. A disk L¹, having a central cylindrical extension L² which surrounds the striker H is seated against a shoulder in the casing A' and the aforesaid disk L, is seated against the disk L¹, both disks being kept from turning within the shell by a pin l. The upper surface of the disk L is grooved to form a ball-race L³ for the balls of the thrust bearing of the cam. The cam itself is shown at P and is of an annular form surrounding the hammer and mounted to rotate on the balls forming the thrust bearing aforesaid. The

inclined surfaces of the cam are shown as forming a series of saw tooth or ratchet-tooth points indicated at p^1 and p^2 . In the illustrated machine there are three of these 5 points equally spaced apart around the circumference of the cam. They form maximum points for the cam and coöperate with three rollers J projecting radially from the enlarged head H^2 of the hammer. By means 10 of such a plurality of maximum lifting points on the cam the lifting strain is substantially symmetrical with respect to the axis of the hammer and side thrust on the hammer is avoided. The cam P is connected 15 with a hollow cylinder, or sleeve, R which is provided near its upper end with internal gear teeth S. The internal gear, as appears more clearly in Fig. 4, meshes with idler pinions S^1 which, in turn, mesh with a gear 20 S^2 on the motor shaft. The pinions S^1 are mounted on studs projecting from the under side of the aforesaid disk F which pertains to the shell A. Thus by unscrewing the joint between the casing sections A and A' the 25 tool may be separated, the pinions S^1 together with the motor and the pinion S^2 going with the part A, while the internal gear S goes with the part A'. When the two parts of the tool are thus separated, the hammer element 30 together with the cam and the spring may be lifted out through the open end of the section A'. Then by unscrewing nut h, the hammer, the cam and the spring may be taken apart. That is, the three parts just 35 mentioned form a unitary structure which can be inserted as a whole in the casing-section A'. It will be manifest that when the motor rotates the driving pinion S^2 , acting through the idlers S^1 will rotate the cylinder or sleeve R together with the cam P. The lifting points of the cam will act periodically to raise the hammer and compress the spring K, the hammer being prevented from rotating by means of the squared portion H^1 . When the rollers drop off the lifted 45 points of the cam, the spring will be released and will force the descent of the hammer to give the impact or blow of the hammer upon one end of the anvil or tool T. Any desired form of tool T may be employed 50 or the hammer H may be itself extended through the lower end of the casing A' to serve as the impact member. It may also be noted that while the annular cam 55 rounds the hammer which passes axially therethrough, the cam is driven by the sleeve R and the gearing which we have heretofore described. The sleeve and gears form a driving connection, between the armature 60 shaft and the cam, which extends around or outside of the rollers J which form the extensions from the hammer that engage and travel upon the working surfaces of the cam.

The electric motor when of the D. C. type 65 has its field magnet and its armature in se-

ries in order to give the periodic torque-impulses required to lift the hammer against the aforesaid spring. The motor is controlled by a simple switch W and is located in the handle of the tool, being operated by 70 a push button W^1 which projects through the side of the handle.

What we claim as new and desire to secure by Letters Patent is:

1. An automatic hammer comprising a 75 striker, an actuating spring therefor, an electric motor, an annular lifting cam surrounding the hammer and engaging the spring, extensions on the hammer engaging said cam and a driving connection between the motor 80 and the cam passing outside of said extensions.

2. An automatic hammer comprising a 85 striker, an actuating spring therefor, an electric motor having its shaft in line with said striker, an annular lifting-cam surrounding the hammer, an extension on the hammer engaging said cam and a driving connection between the motor-shaft and cam which passes outside of said extension. 90

3. An automatic hammer comprising a 95 striker and an actuating spring therefor, an electric motor having its shaft in line with said striker, an annular lifting-cam surrounding the hammer, an extension on the 100 hammer engaging the said cam, and a gear-connection between the motor-shaft and cam which passes outside of said extension.

4. An automatic hammer comprising a 105 striker and an actuating spring therefor, an electric motor having its shaft in line with said striker, an annular lifting-cam surrounding the hammer and acting on the spring, a cam-gear connected to the cam, a pinion on the motor-shaft and a gear wheel 110 between said pinion and said cam-gear.

5. An automatic hammer comprising a 115 striker and an actuating spring therefor concentric with the striker, and an electric motor having its shaft in line with the 120 striker, a cam device for tensioning and releasing the spring located between the spring and the motor, and a driving connection between said cam-device and the motor.

6. An automatic hammer comprising a 125 striker, an actuating spring in the lower part of the hammer concentric with the striker, an electric motor in the upper part of the hammer, an intermediate annular cam acting on the spring, and a driving connection 130 external to the cam between the cam and the motor.

7. An automatic hammer comprising a reciprocating striker and an actuating spring therefor, an annular cam loosely engaging 135 the striker, rollers carried by the striker and positioned to engage the working face of the cam, means for preventing rotation of the striker, a friction-roller thrust-bearing for the cam, an electric motor, and a gear 140

connection between the motor and the cam by means of which said cam is rotated.

8. An automatic hammer comprising a reciprocating striker, and an actuating spring therefor, an electric motor, a casing formed of two separable sections, one of which sections incloses the motor and forms part of its magnetic circuit, the other section inclosing the striker, a cam operated by the motor and rotatable independently of the striker, and means on the striker coöperating with said cam to periodically compress and release the spring.

9. An automatic hammer comprising a reciprocating striker, an actuating spring therefor, a casing extending longitudinally of the said striker, an electric motor having its shaft in line with the striker, a cam device driven by the motor independently of the striker and operating transversely to the axis of the striker, and means on the striker coöperating with said cam to periodically tension and release the spring.

10. An automatic hammer comprising a reciprocating striker, an actuating spring therefor, an electric motor, an intermediate cam driven by the motor to periodically tension and release the spring, and a longitudinal casing one detachable section of which 25 serves as a part of the magnetic circuit of the motor and is provided with motor bearings while the other section receives the reciprocating striker, the spring and the spring-actuating cam.

35 11. An automatic hammer comprising a striker, an actuating spring therefor, an electric motor, a cam driven by the motor to periodically tension and release the spring, and an inclosing casing, the spring 40 being held between abutments which are removable bodily from the casing together with the spring.

12. An automatic hammer comprising a striker, an actuating spring therefor, an electric motor, a cam driven by the motor to periodically tension and release the spring, a casing, members on the striker between which the spring is held under tension, the striker together with said members 50 and the spring being bodily removable from the casing and detachable from the remain-

ing mechanism, a stop on the striker against which one end of the spring abuts, an annular cam, an extension on the striker bearing on the working surface of said cam and held thereon by the tension of the spring and a bearing for the cam sustained by the casing.

13. An automatic hammer comprising a reciprocating striker and an actuating spring 55 therefor, an annular spring-tensioning cam surrounding and loosely engaging the striker, said cam having maximum points on opposite sides of the striker axis, and an electric motor operatively connected with said cam to rotate the same.

14. An automatic hammer comprising a reciprocating striker, and an actuating spring therefor, an electric motor, a casing, a transverse member in the casing through 70 which the striker reciprocates, a cam loosely engaging said striker and rotatably engaging said transverse member through an interposed thrust-bearing, rollers on the striker traveling upon the working surface 75 of said cam and a driving connection between said cam and the motor, whereby the cam is rotated.

15. An automatic hammer, comprising a reciprocating striker, a spring surrounding 80 the striker, a cam mounted to rotate independently of the striker, means on the striker coöperating with said cam for alternately tensioning and releasing the spring, an electric motor and a two-step gear opera- 85 tively connecting said cam and motor.

16. An automatic hammer comprising in combination a two-part cylindrical casing one part containing an electric motor having its shaft extending longitudinally of the 90 casing and provided with a handle for the hammer, the other part being in line with the first part and containing a reciprocating striker, an actuating spring therefor abutting at one end on the casing and at the 95 other end on the striker, a cam for alternately tensioning and releasing the spring, and a separable driving connection between said cam and the shaft of the motor.

Signed this 25th day of September, 1917. 100

GEORGE L. KOLLOCK.
